METHOD AND APPARATUS FOR COVERING
A SCALE FOR THE HANDLE OF A POCKET
KNIFE

Paul Richartz, Sheffield, England

Application September 22, 1945, Serial No. 617,997

4 Claims. (Cl. 18—19)

1

This invention relates to an improved method and apparatus for covering a scale for the handle of a pocket knife with a sheet of deformable material, such as thermoplastic sheet and has for an object to provide means for mechanically applying the sheet material without harmful effects to it.

It has already been proposed to apply a sheet of thermoplastic material to a knife scale by employing a sheet of sufficient size as to provide 10 marginal edges which may be folded over the edges of the scale, and by applying heat more intensely to the folds than to the remainder of the material, and by engaging said marginal edges by members which during their inward movement over the scale, are arranged to compress the thermoplastic material between them and the edges of the scale so as to subject the material to tension. It is found in practice that the folds thus formed are liable to be weakened by the combined heating and stretching, and the present invention has for an object to avoid that defect.

According to this invention, a method for covering a scale for a pocket knife with deformable sheet material consists in placing the sheet material over the cavity in a mould shaped to the contour of the scale, placing the scale on the sheet material over the cavity, forcing the scale and sheet material into the cavity, which material is so dimensioned that its marginal edges project away from the mould and from the edges of the scale, applying lateral forces to said marginal edges over an area spaced away from the edges of the scale by an amount greater than the thickness of the material, whereby the material is bent over the edge without excessive stretching. If necessary, the above steps are followed by applying pressure to said bent-over marginal portions in a direction towards the face of the scale. This latter step is particularly suitable when a hollow-pressed metal scale is employed, and wherein the marginal edges of the material are required to lie wholly within the hollow of the scale.

In the case where a thermoplastic sheet is employed, it is heated substantially uniformly over its area so as to render it permanently deformable, so that when said marginal edges are folded over the scale, they remain permanently set.

In the case where the metal scale is provided

with upraised bolsters, the deformable material is so dimensioned that its end marginal edges are located adjacent the upraised bolsters.

The invention is also applicable to covering a scale with deformable material around an upstanding ornamentation such as a shield, in which case the cavity in the mould is provided with a recess having sharp edges conforming to the shape of the upraised ornamentation, so that when the scale and the sheet material are forced into the cavity, the upraised portion enters into a recess and the sharp edges cut through the material, whereby the cut portion may be removed to expose the ornamentation.

15 An apparatus for carrying out the above process may comprise a press, a mould having a cavity shaped to the contour of the scale, a reciprocable press tool operated by said press and adapted to force said sheet material backed by 20 the scale into the mould, which material is so dimensioned that its marginal edges project from the mould, laterally slidable shutters associated with said mould and adapted to engage said marginal edges at a distance away from the edges 25 of the scale by an amount greater than the thickness of the material, means for applying reciprocable movement to said shutters. In the case where a thermoplastic sheet is employed, means are provided for heating said mould. Preferably, means are provided for locating the sheet material backed by the scale over the cavity in 30 the mould.

In order to prevent the sheet material from being compressed and stretched during the movement of the shutters, the depression in the mould may either be arranged so that the edges of the scale lie substantially flush with the face of the mould and the shutters are guided so as to be spaced away from the top of the mould by an 35 amount greater than the thickness of material, or the depression in the mould may be such that the edges of the scale lie beneath the top face of the mould by an amount greater than the thickness of material, and the shutters are arranged 40 to slide over the top face of the mould.

Movement may be imparted to the shutters by a flexible element attached to each of them and passing over a guide pulley and by a pedal lever 45 attached to the ends of the flexible element, resil-

ient means being provided to resist the movement applied to the shutters by the pedal.

The reciprocable press tool may also be arranged to be operated by a foot pedal. Thus, when the first said pedal is depressed to open the shutters by one foot, the other pedal is operated by the other foot.

The means for heating the mould may comprise a base plate on which the mould and sliding shutters are mounted, to the back of which base plate there is secured an electric heating element. By these means, the whole of the mould and the shutters are heated to a uniform temperature.

The following is a description of one form of apparatus, and two alternative constructions of mould for forming a knife scale according to this invention, reference being made to the accompanying drawings, in which—

Figure 1 is a side elevation of the apparatus;

Figure 2 is a plan view on an enlarged scale of one form of mould and associated shutters;

Figure 3 is a section on the line 3—3 of Figure 2;

Figure 4 is an enlarged view of a part of Figure 3 showing the initial position of the sheet Celluloid covering and hollow metal scale in relation to the mould;

Figure 5 to 7 show the covering and scale after successive operations carried out by the apparatus;

Figure 8 is a similar view of Figure 2, showing an alternative form of mould;

Figure 9 is a cross-section on the line 9—9 of Figure 8;

Figure 10 is a cross-section on the line 10—10 of Figure 8;

Figure 11 is a plan view of an alternative mould block; and

Figure 12 is a section through a hollow pressed metal scale having an ornamentation and which is covered by means of the mould block of Figure 11.

Referring to the construction shown in Figure 2, the mould comprises a base plate 10 on which are secured end blocks 11 and 12 by set-screws 13. The blocks are provided with vertically-extending grooves 14 and 15 facing one another, and the contours of which grooves correspond with the contours of the bolster of the knife. A main mould block 16 is disposed between the end blocks 11 and 12 and is provided with a depression 17 in the upper face thereof corresponding in shape to the shape of the knife scale. The main mould block 16 is provided with end pieces 18 and 19 which engage the grooves 14 and 15 in the end blocks, thereby maintaining the main block in position, but so that it can be readily removable. In the case where the bolster end of the metal knife scale is provided with a lug by which it is attached to the skeleton of the knife, the block 11 may be provided with a recess 20 extending partly down the depth of the block for initially accommodating the lug, but which serves to bend the lug during the operation of the apparatus, as hereinafter described. Mounted in slideways 21 on either side of the main mould block are flat shutters 22, which slideways are so located that the shutters may move over the top of the main mould block 16 and meet one another, as shown in Figure 3. The shutters are urged towards one another by means of tension springs 23 secured at one end 24 to the shutters, and at the other end 25, to the base plate 10. The shutters may be moved

70
75

apart by chains 26 secured to them at 27 and passing over sprocket wheels 28 mounted in suitable recesses 29 at the sides of the base plate. The base plate is heated beneath the main mould block 16 by an electric heating element 30 attached to the underside of the base plate. The degree of heating may be controlled by a switch 31 which connects in varying lengths of the resistance to the electric supply.

An alternative form of mould is shown in Figures 8 to 10. In this arrangement, the mould block 16 is mounted to slide vertically in a casing part 61 secured to the base plate 10. As in the previous construction, shutters 22 are arranged to slide in slideways 21 and are operated against the action of springs by means of chains 26. In this instance, however, the top face of the casing part 61 is recessed at 54 to provide channels in which the shutters may slide, either by forming the recesses in the material of the casing part, or as shown in Figure 10, providing spacing members 62 at its ends, and the slides 21 are prevented from rising in these recesses by a cover plate 55 secured over the top of the casing part 61 by studs 56. The cover plate is provided with an aperture having edges 57 and 58 so shaped and disposed as to register the sheet Celluloid correctly over the recess in the mould. It is also provided with other edges 59 and 60 shaped to correspond with the bolster ends of the scale and guide it correctly into engagement with the depression 17 in the mould block 16, except, in this instance, the shutters 22 slide over the top face of the mould block 16 within the aforesaid casing. The depth of the portion 17 of the mould part is sufficiently great that when the metal scale and Celluloid sheet have been pressed into it, the edges of the metal scale lie below the top of the mould block by an amount greater than the thickness of the Celluloid sheet. Thus, when the Celluloid sheet is bent over the edges of the metal scale by the slides 22, it is not subjected to compression or excessive stretch, as referred to above.

It is usual for the covering of the scale to lie flush with or slightly below the surface of the bolsters, and for this purpose, the scale is initially hollow-pressed, to provide a countersunk portion between the bolsters which are left up-standing, and the edges of the scale are recessed between the bolsters by an amount equal to or greater than the thickness of the Celluloid sheets. In order that the mould block 16 may be readily removed from the casing part 61, the bottom wall 63 of the casing is provided with two holes 64 through which extend two pins 65, actuated by the forked end of a lever arm 46 having a manipulating handle 47.

As will be seen from Figure 1, the base plate 10 and the mould on it are secured to the base 32 of a foot-operated press 33 mounted on a pedestal 34. The press is provided with a square-section plunger 35 reciprocably mounted in bearings 36 at the ends of cantilever arms 37. The plunger is provided with a slot 38 in which is located the end of a lever-arm 39. The lever-arm is pivoted at 40 in the main upright portion of the press, and is provided with a double cranked arm 41 extending downwardly, and then forwardly, where it is provided with a pedal extremity 42. The two chains 26 extend downwardly from the sprocket wheel 28 and are attached at their lower ends to a foot-lever 43 pivoted at 44 to the back of the pedestal, and provided with a pedal 45. Thus, by depressing the

pedal 45 the aforesaid shutters 22 are drawn apart against the action of the springs 23. The lower end of the plunger 35 has secured to it a press tool 48, the end of which is shaped to correspond with the internal contour of the hollow-pressed metal scale.

The operation of applying the Celluloid sheet covering to the metal scale is now described with reference to Figures 4 to 7, which embody a mould and shutters as described with reference to Figures 2 and 3. The temperature of the base plate 10 is so adjusted to a degree which will render the Celluloid sheet pliable. The foot pedal 45 is depressed so as to separate the shutters 22, and, as seen in Figure 4, the Celluloid sheet 49 is first laid over the main mould block 16, which sheet is so dimensioned as to extend between the bolster ends of the sheet metal scale 50 and is sufficiently wide as to permit it eventually to be bent around the curved contour of the scale, and then inwardly over the edges of the scale, as shown in Figure 7. The Celluloid sheet while in the position shown in Figure 4 is raised to substantially the same temperature over the whole of its area so as to render it deformable.

As indicated earlier in the specification, the bolster ends of the scale may be provided with lugs 51, and the metal scales are inserted between the blocks 11 and 12, with the lugs in the slots 20. The slots 20 are of sufficient depth to permit the scale to rest on the Celluloid sheet 49, as shown in Figure 4.

The next operation consists in forcing the hollow metal scale and Celluloid covering into the mould part 16 by means of the press tool 14 which is forced downwardly by pressure on the foot-pedal 42 by one foot, while the other foot maintains the other pedal 45 depressed. The marginal edges 52 of the Celluloid sheet are caused by this operation to extend upwardly, and the parts remain in this position during the operation of withdrawing the press tool 48. The next operation, which is shown in Figure 6, consists in moving the shutters comparatively rapidly inwardly and outwardly. This is effected by momentarily releasing the pressure on the foot-pedal 45. The above steps follow one another in such quick succession that although the marginal edges momentarily leave the face of the mould they remain at substantially the same temperature as the remainder of the sheet which is sufficient to render the sheet deformable.

It will be noted that the shutters 22 are so disposed in their slides 21 as to leave a gap 52 of greater width than the thickness of the Celluloid sheet between the shutters and the mould part 16 and the edges of the scale. The sheet is thus bent over the edges of the hollow-pressed metal scale 50 by a simple bending movement, without submitting it to any excessive stretching action which might otherwise fracture it at the bend. As already indicated, the Celluloid sheet has been rendered pliable over its whole area, including the region of the edges of the metal scale, and the effect of this folding operation is permanently to distort the material at the bend, so that when the shutters are removed, it remains substantially in the same condition as that shown in Figure 6.

In order that the marginal portions 52 may be made to lie flush against the inside of the hollow metal scale, the press tool 48 is again lowered, as shown in Figure 7, and after withdrawal thereof, the operation is complete.

The hollow-pressed metal scale may also be 75 cavity, said material being so dimensioned that

embossed to provide an upstanding ornamentation, such as a shield 55, at a location between the bolsters and the mould may initially be provided with a recess 56 having a sharp cutting edge shaped to register with the upstanding ornamentation, so that after the sheet scale has been subjected to pressure in the mould, the ornamentation lies flush with the surface thereof.

I claim:

1. An apparatus for covering a scale for a pocket knife with deformable sheet material, comprising a press, a mould having a cavity shaped to fit said scale and so that the edges of the scale lie beneath the face of the mould by an amount greater than the thickness of the sheet material, a reciprocable press tool vertically operated by said press and adapted to force said sheet material backed by the scale into the mould, said press tool having a width equal to the width of the scale to contact the entire width of the scale during the pressing operation and said material having its marginal edges projecting from the mould, laterally slidable shutters movable horizontally and associated with said mould to engage said marginal edges, means for applying reciprocable movement to said shutters so that they slide on the surface of said mould into engagement with the marginal edges of the material, and means for applying reciprocable movement to said shutters, and means for heating said mould.

2. An apparatus for covering a scale for a pocket knife with deformable sheet material, comprising a press, a mould having a cavity shaped to the contour of the scale, a reciprocable press tool, a foot pedal connected to operate said press tool and to force said sheet material backed by the scale into the mould, said material having its marginal edges projecting from the mould, laterally slidable shutters, sideways for said shutters adapted to guide them into engagement with said marginal edges, a flexible element attached to each shutter and passing over a guide pulley, a foot pedal lever attached to the ends of the flexible elements, resilient means resisting the movement applied to the shutters by the pedal and means for heating said mould.

3. A method of covering a scale for a pocket knife with deformable sheet material which consists in placing the sheet material over the cavity in a mould shaped to the contour of the scale, placing the scale on the sheet material over the cavity, applying vertical pressure over the greater part of the area of the scale so as to force it and the sheet material into the cavity, said material being so dimensioned that its marginal edges project away from the outer face of the mould and from the edges of the scale, applying horizontal forces to said marginal edges over an area spaced away from the edges of the scale by an amount greater than the thickness of the material to bend the material over the edge of the scale without excessive stretching, and applying vertical pressure to said bent-over marginal portion in a direction towards the base of the scale to force them marginal portion against the inside cavity of the scale.

4. A method of covering a scale for a pocket knife with deformable sheet material which consists in placing the sheet material over the cavity in a mould shaped to the contour of the scale, placing the scale on the sheet material over the cavity, vertically moving a press tool on the scale and sheet material to force them into the cavity and thereafter moving the press tool out of the

its marginal edges project away from the mould and from the edges of the scale, applying lateral forces to said marginal edges by horizontally movable shutters over an area spaced away from the edges of the scale by an amount greater than the thickness of the material to bend the material over the edge without excessive stretching, and vertically moving the press tool against the bent sheet material to apply pressure on the bent over marginal portions in a direction towards the face of the scale to force the marginal edges against the inside of the scale.
